(57) CLAIM

The ornamental design for a light as shown and described.

DESCRIPTION

FIG. 1 is a top perspective view of a light illustrating our new design.

FIG. 2 is a bottom perspective view thereof.

FIG. 3 is a top view thereof.

FIG. 4 is a bottom view thereof.

FIG. 5 is a front view thereof.

FIG. 6 is a rear view thereof.

FIG. 7 is a right-side view thereof.

FIG. 8 is a left-side view thereof.

FIG. 9 is a top perspective view of FIG. 1 shown in an alternative environment of use.

FIG. 10 is a bottom perspective view thereof.

FIG. 11 is a top perspective view of FIG. 1 shown in an additional alternate environment of use.

FIG. 12 is a bottom perspective view thereof.

FIG. 13 is a top perspective view of FIG. 1 shown in another alternate environment of use; and,

FIG. 14 is a bottom perspective view thereof.

Portions of the light are shown in broken lines. Portions shown in broken lines form no part of the claimed design. The light is shown with a symbolic break in its length. The appearance of any portion of the article between the break lines forms no part of the claimed design.

1 Claim, 14 Drawing Sheets
